United States Patent Office

Des. 177,808
Patented May 29, 1956

177,808

AWNING

Herbert M. Helt, Pittsburgh, and Philip Fellman, Library, Pa., assignors to National Aluminum Products Company, Pittsburgh, Pa., a corporation of Pennsylvania

Application February 21, 1955, Serial No. 34,603

Term of patent 3½ years

(Cl. D21—6)

FIG. 1

FIG. 3

FIG. 2

Figure 1 is a perspective view of an awning, showing our new design,

Figure 2 is an enlarged perspective view of a fragmentary corner portion of the top thereof shown in Figure 1 illustrating the crinkly formation thereof on both surfaces of the material, and

Figure 3 is a cross-sectional view taken along line III—III of Figure 2.

The characteristic features of our new design are shown in full lines.

This application is a continuation-in-part of our co-pending application, Serial No. D. 29,417, filed March 8, 1954, now abandoned.

We claim:

The ornamental design for an awning, substantially as shown and described.
